UNITED STATES PATENT OFFICE.

WILSON R. BLAIN, OF ALBANY, OREGON.

DESIGN FOR A UNION SUIT.

44,604.

Specification for Design.

Patented Sept. 2, 1913.

Application filed July 10, 1913. Serial No. 778,388. Term of patent 14 years.

To all whom it may concern:

Be it known that I, WILSON R. BLAIN, a citizen of the United States, residing at Albany, in the county of Linn and State of Oregon, have invented a new, original, and ornamental Design for Union Suits, of which the following is a specification.

Reference being had to the accompanying drawing forming a part thereof, Figure 1 is a front perspective view of a union suit showing my new design. Fig. 2 is a rear perspective view.

I claim:

The ornamental design for a union suit as shown.

WILSON R. BLAIN.
